UNITED STATES PATENT OFFICE

BENJAMAN W. BROWN, OF HAPEVILLE, GEORGIA, ASSIGNOR OF ONE-HALF TO JAMES CHAPMAN AND ONE-FOURTH TO LAURA EMILY SCOTT CHAPMAN, BOTH OF ATLANTA, GEORGIA

PROTECTOR MECHANISM FOR LOOMS

Application filed June 18, 1930. Serial No. 462,042.

My said invention relates to an improvement in protector mechanism for looms and it is an object of the invention to remove from the shuttle as it enters and leaves the shuttle box substantially all that spring pressure which has heretofore been placed on it by the protector mechanism commonly in use. By removing the principal part of such spring pressure the shuttle enters and leaves the shuttle boxes only against very light pressure, the protector rod remaining dormant until just before the protector dagger reaches the knock-off or slam steel when it is raised mechanically without jar or vibration so as to pass over or under the knock-off as the case may be thereby preventing what is known as "tipping off the loom". The absence of substantial pressure prevents heating of the shuttle, prevents wearing of the shuttle to sharp or wedge ends, does not cause bursting out of the pickers on the picker sticks as the shuttle is not driven so hard and avoids strain on the picker sticks, lug straps and pick levers as the shuttle is never under severe spring pressure. My construction prevents the shuttle walls from being sprung as the shuttle enters and leaves the box and prevents shuttles from cracking at each end of the shuttle walls. It permits the shuttle boxes to be set up on a straight line either on a back binder loom or on a front binder loom, thereby preventing shuttles from slapping when going into the boxes. It also causes the shuttles to emerge from the boxes in a straight line thereby doing away with the zig-zag movement of the shuttle in its flight across the lay known as "snaking shuttle". It will be understood that the shuttle must be kept from rebounding after it enters the boxes and this is taken care of by the slight pressure of the binder; the shuttle being picked more lightly, a very light protection spring pressure is sufficient to prevent rebounding. All the power required from the pick mechanism is that necessary to throw the shuttle across the lay and the heavy picking necessary ordinarily to box the shuttle in a tight box is done away with (as well as the consequent vibration) this making for a great saving in power.

Another object of the invention is to provide adjusting means whereby the operation of the protection rod may be set precisely for any desired time so as to operate the protection rod only at such time and through mechanical means controlled by the proper boxing of the shuttle but not directly actuated by force derived from the flight of the shuttle. Such means may be simple and positive mechanical means adding very little to the cost of the loom or to the upkeep, particularly when compared with the relatively delicate and expensive shuttle and shuttle box mechanism.

Referring to the drawing which is made a part of this application and in which similar reference characters indicate similar parts,

Fig. 1 is a fragmentary front elevation of the lay and associated parts,

Fig. 2, a fragmentary section on line 2—2 of Fig. 1,

Fig. 3 is a section on line 3—3 of Fig. 1, and

Fig. 4, a modification.

In the drawing reference character 10 indicates one side member of a loom frame on which the rocker shaft 11 for the lay 12 is supported, the lay being mounted on the rocker shaft by lay swords 13 as usual and being operated by a crank shaft 14 and link 15 in well known manner, said lay having associated therewith a reed 16, reed cap 17 and shuttle boxes 18 and 19 (Figs. 2 and 3), all of which are or may be substantially of any conventional or desirable type. A pick shaft 20 of ordinary type is also shown as being supported by the frame of the loom, said shaft being driven by the crank shaft 14 in the usual two and one speed relation.

The shuttle boxes are each supplied at their forward side with shuttle binders 21 pivoted at 22. These shuttle binders serve, as usual in the art, to retard the shuttle, indicated diagrammatically at 23, as it enters the shuttle box to prevent rebounding and to control the operation of the protector mechanism. The shuttle binders are forced lightly inward toward the shuttle by light flat springs 24 provided at their inner ends with sockets 25 for receiving the upper ends 100

of protector fingers 26 which are pivotally mounted on rock arms 27 adjustably secured to the protector rod 28 by means of set screws 29. This protector rod also carries a dagger 30 as shown in Fig. 1. It will be understood that the spring 24 may be separate from the socket 25. The protector rod is mounted for oscillatory movement and is biased for movement in a counterclockwise direction by means of a spring 31 as usual in such devices. This spring may be set at one uniform and very light pressure as it has only to hold the protection rod in normal position against the weight of finger 26, etc., and does not react against the pressure of the shuttle in the shuttle box.

Levers 32 are here shown as being pivotally mounted on the lay and each of said levers is connected at its free end to a link 34 having a hooked end entering an aperture in the lever. At their lower ends the links 34 are connected to levers 35 having removable cams at 36 adapted to be acted on by wrist pins 37 on cams 38. These cams may be the usual pick cams or additional cams on the pick cam shaft or they may be cams on a shaft other than the pick cam shaft, according to the type of loom and the other exigencies of the situation.

In the use of my invention the shuttles are picked across the fell of the forming cloth as usual from one shuttle box to the other. The shuttle binders are held lightly so as to be slightly in the path of the shuttles so as to check but very little the movement of the shuttle and to retard it sufficiently to prevent its rebounding out of the box. A properly boxed shuttle swings the binder back slightly about its pivot 22 against the tension of spring 24 or equivalent means. This causes the finger 26 to swing to the right about its pivot on rock arm 27 so as to bring a lug 40 on the finger into the path of movement of the lever 32. It will be understood that the distance between lever 32 and finger 26 is considerably exaggerated for clear disclosure. This lever being moved in timed relation with the picks of the shuttle and the movements of the lay will now pull down on the finger 26 and turn the protector rod 28 just in time to prevent the dagger 30 from striking a knock-off lever or equivalent device, which may be such as is illustrated in the patent to McMichael 1,495,606 or may be of any other suitable type. If the shuttle is not properly boxed the binder will not be forced back and the protection finger will remain in a position to the left of that indicated in Fig. 3 so that the lever 32 will not strike the lug 40. This therefore leaves the protector rod in normal position where the dagger will strike a knock-off lever or the like, thus stopping the loom.

The set screw 29 provides for adjustment of the rock arm 27 about the rod 28 to any

desired position so as to bring the lug 40 to the desired height relative to lever 32 for swinging the rod 28 to the extent desired and at the proper time. A further adjustment may be had at the pivot 40 of lever 35 by means of an eccentric pivot 41 shown in Fig. 2, or other suitable means, and the length of rod 34 may also be changed by turnbuckle 34' for like purposes.

In Fig. 4 I have shown a slight variation of my device whereby the finger 26' is mounted for oscillation about a pin 43 on the rock arm 23 and is normally held in the illustrated position by means of a coil spring 42. The purpose of this construction is to prevent any breakage of the shuttle, the binder or other parts in case a shuttle should stick in the shuttle box, in which case the spring will permit the finger to yield at its lower end by moving to the left in Fig. 4.

It will be obvious to those skilled in the art that numerous changes may be made in my device without departing from the spirit of the invention and therefore I do not limit myself to what is shown in the drawing and described in the specification but only as indicated in the appended claims. For example it will be obvious in applying my device to a back binder loom that the parts will have to be supported in slightly different manner. Again in applying it to a Draper loom the shape of the lever 35 will have to be changed, but all such minor mechanical variations are regarded as being within the skill of the ordinary mechanic skilled in this art and are therefore not illustrated in the drawing. It should be understood as to the shuttle binders and as to other parts not specifically described as new that these parts may be of any conventional or desirable character as found in commercial looms.

Having thus fully described my said invention, what I claim as new and desire to secure by Letters Patent is:

1. In a loom having a lay and protector mechanism including an oscillatory protector rod and a dagger fixed to the rod, the combination of a shuttle box, a shuttle binder for said box, a rock arm fixed to the protector rod, a protector finger pivoted on said rock arm said finger having a lug and being connected to the shuttle binder for oscillation about its pivot on the rock arm, a lever pivoted on the lay, and means for oscillating said lever in timed relation with the movement of the lug to engage it with said lug if the shuttle is properly boxed thereby preventing operation of the protector mechanism to stop the loom, substantially as set forth.

2. In a loom having a lay and protector mechanism including an oscillatory protector rod and a dagger fixed to the rod, the combination of a shuttle box, a shuttle binder for

said box, a pivoted lever, means for moving said lever in timed relation to the movements of the lay, a rock arm fixed to the protector rod, a protector finger pivoted on the rock arm said finger being moved outward by the shuttle binder upon boxing of the shuttle, and means whereby said pivoted lever acts on the protector mechanism through said protector finger and rock arm to turn the protector rod and so prevent knocking-off when the shuttle is properly boxed, substantially as set forth.

3. In a loom having a lay and protector mechanism including an oscillatory protector rod and a dagger fixed to the rod, the combination of a shuttle box, a shuttle binder for said box, a rock arm fixed to the protector rod, a protector finger pivoted on said rock arm, said protective finger being connected to the shuttle binder for oscillation thereby, and means controlled by the position of the shuttle binder for operating on the protector mechanism through said finger at each pick of the shuttle if the shuttle is properly boxed so as to prevent knocking-off of the loom, substantially as set forth.

4. In a loom having a lay and protector mechanism including an oscillatory protector rod and a dagger fixed to the rod, the combination of a shuttle box rock arm fixed to the protector rod, a shuttle binder for said box, a rock arm fixed to the protector rod, a protector finger connected to the shuttle binder to be positioned thereby said finger being loosely pivoted on said rock arm, and means for acting on said finger, at each pick of the shuttle if the shuttle is properly boxed so as to rock said protector rod and prevent knocking-off of the loom, substantially as set forth.

5. In a loom having a lay and protector mechanism including an oscillatory protector rod and a dagger fixed to the rod, the combination of a shuttle box, a shuttle binder for said box, a rock arm fixed to the protector rod, a protector finger pivoted on said rock arm, said rock arm being connected to the shuttle binder for oscillation thereby, and power-operated means for oscillating the protector rod to prevent knocking-off of the loom, said means acting after said finger has been swung out due to proper boxing of the shuttle, substantially as set forth.

In testimony whereof I affix my signature.
55 BENJAMAN W. BROWN.
